STORM WINDOW

Joseph Sylvan, Berkley, Mich.

Application August 7, 1944, Serial No. 548,385

3 Claims. (Cl. 160—91)

1

This invention relates to improvements in storm or supplemental windows, and one of the objects of the invention is to provide an improved frame, and improved means whereby the same may be secured in position with respect to the ordinary window structure, without the use of screws, bolts, or other fastening means, and in which frame an upper and a lower sash are arranged.

A further object is to provide an improved window construction of this character, adapted to receive a screen which co-operates with the window sashes, whereby to provide a storm or supplemental window, adapted for use in any kind of weather.

Other and further objects will appear from the following specification and claims, in connection with the accompanying drawings, in which:

Fig. 1 is a front elevation of a storm window constructed in accordance with the principles of this invention.

Fig. 2 is an enlarged detail, horizontal, sectional view, taken on line 2—2, Fig. 1, showing one of the sashes partially in position.

Fig. 3 is an elevation, partly broken away, of the window sash frame, and showing, in dotted lines, parts of the frame in adjusted position.

Fig. 4 is an enlarged detail, sectional view taken on line 4—4, Fig. 3.

Fig. 5 is an irregular vertical, sectional view, on an enlarged scale, taken on line 5—5, Fig. 1, with parts broken away.

Fig. 6 is a detail sectional, perspective view taken on line 6—6, Fig. 1.

Referring more particularly to the drawings, the numeral 10 designates side members or uprights constructed of metal and of a length only slightly less than the length of the side of a window frame or casing 11. Each of these side members or uprights is shaped to form a channel 12, of a width slightly less than the width of a guide member 13 of the window frame, and which window frame and guide members are usually constructed of wood, and along which guide members the upper and lower sashes of the window move. Each of the uprights is shaped to form two pockets or grooves 14—15, arranged in close proximity, and one in advance of the other. These pockets or grooves open in the same direction and in a direction opposite to the direction in which the channel 12 opens. The pocket or groove 15 is of a depth somewhat greater than the depth of the pocket or groove 14, for a purpose to be described, and both of the pockets extend

substantially throughout the length of the uprights.

In use, the uprights 10 are positioned adjacent the opposite sides of the window frame, with the pockets or grooves 14 and 15 of the opposite uprights opening towards each other, and with the channels 12 disposed to be snapped or forced over the respective upright guide members 13 of the window frame. These channels, when forced into position over the guide members 13, will hold the uprights frictionally in position, without the use of screws, nails, or any other fastening or securing means.

Arranged adjacent the upper ends of the uprights 10, and supported thereby, is a top cross bar or frame member 16, which is shaped to form a channel 17 adapted to engage over or receive a cross frame member 18 of the window casing, and behind which frame member the top bar 19 of the upper sash frame passes. The outer edge of the top member 16 is shaped to form a downwardly opening channel 20, and the channel 17 is of a width that the channel 20 will be in alignment or register with the pockets or grooves 14 in the uprights 10. Should the channel 17 be of a width greater than the thickness of the cross member 18 of the window frame, the space formed therebetween may be filled with any suitable material or caulking 20a.

Slidable in the pocket or groove 14, is a bottom window sash 21, and slidable in the pocket or groove 15 is an upper sash 22. These sashes are held in the positions to which they have been moved, by friction created between the walls of the pockets or grooves and the respective window sash.

A screen 23 is also adapted to be placed within and so as to move in the pocket or groove 15, below or above the upper sash 22, as desired.

In assembling the structure, the cross member 16 at the top of the frame, and one of the uprights 10, are placed in position, after which one side of each of the sashes 21 and 22 is placed within the respective grooves or guideways 14—15 in the upright that is attached to the window frame. Owing to the depth of the guideways 14—15, the sides of the sashes may be inserted thereinto, for a distance to permit the opposite upright 12 which has been telescoped over the other sides of the sashes, to swing clear of the opposite upright guide member 13, so as to position the last said upright 12 to be sprung over the adjacent upright guide member 13, as shown in Fig. 2. Thereafter, the sashes may be adjusted edgewise to center the sashes in the frame. Fric-

tion will maintain the sashes in their proper positions with respect to the uprights. The screen 23 may be similarly placed in position, either above or below the upper sash, according to the area in which ventilation is desired. However, if desired, and if there is sufficient space to permit, without spreading the sides of the sash 22 too much, in order to fill the pockets or guideways 14-15, both of the uprights 12 may be placed in position, and then one side of the respective sashes 21-22 may be inserted into the guideway or pocket, a sufficient distance to allow the other side to swing clear of the adjacent upright and into position in alignment with the pocket or guideway in the last said upright. The sash may then be adjusted laterally into proper position so as to slide freely in its guideways or pockets.

Thus it will be seen that there is provided a simple and efficient storm sash or window, which may be readily installed without the use of screws, nails, or other fastening means, and which structure may be as readily removed.

The window sashes 22-23 are of metal construction, and frames thereof are adjustable, to adapt the same to be readily adjusted to fit within the frame. To that end, each of the sashes embodies side members 24, of channel formation, to receive the side edges of the glass 25. The ends of the side members are bent or lapped over the ends of the respective upper and lower cross bars or members 26, as at 26a, so as to hold the parts in position and, at the same time, permit of lateral adjustment of the side bars or members 24.

If desired, the lower cross bar or member 26 of the upper sash 22 may be shaped to form a hand grip 27, the bent portion 27a of which will also serve to fill in the space between the two sashes, and provide a weather seal. The bottom cross member 28 of the lower sash may also be shaped to provide a hand grip 29, and this grip may also be shaped to form a receptacle or support for the screen 23. When the latter is not in use, and when the screen is positioned in the receptacle thus formed, and in a substantially upright position, it will not interfere with the raising and lowering of the bottom storm sash. However, when the screen is positioned in the pocket, so that the upper edge of the screen will pass below the bottom rail of the upper sash of the window, to which this invention is attached, the screen will serve as a lock to prevent raising of the lower storm sash and also to prevent lowering of the upper sash of the building window.

While the preferred form of the invention has been herein shown and described, it is to be understood that various changes may be made, within the scope of the claims, without departing from the spirit of this invention.

What is claimed as new is:

1. A window construction embodying a pair of laterally spaced uprights, each of said uprights provided with window sash guideways in proximity to each other, and one being in advance

of the other, and window sashes movable in said guideways, a portion of each of said uprights being shaped to form a channel adapted to receive and frictionally grip an upright of a window casing, and constituting the sole fastening means for securing said window construction in position, each of said sashes embodying a frame having laterally adjustable side members, whereby the width of the sash frames may be varied, and whereby to permit the sash to be positioned between said uprights and into the respective guideways, and also whereby when in such position, the side members of the sashes may be laterally adjusted to substantially fill the respective guideways.

2. In combination, a window construction embodying an upper window sash, a storm window disposed in front of the first said window, said storm window embodying an upper and a lower sash freely slideable with respect to each other, a formation on the lower sash constituting a support, and a screen adapted to be positioned below the lower storm sash when the latter is raised, said screen adapted to be also positioned upon said support, with the upper edge of said screen positioned beneath the bottom rail of the upper sash of the building window, to lock the last said sash against being lowered, and to also lock the lower storm window sash against being raised.

3. In combination, a window construction embodying an upper window sash, a storm window disposed in front of the first said window, said storm window embodying an upper and a lower sash freely slideable with respect to each other, a formation on the lower sash constituting a support, and a screen adapted to be positioned below the lower storm sash when the latter is raised, said screen adapted to be also positioned upon said support in an inclined position, whereby the upper edge of said screen will project beneath the bottom rail of the upper sash of the building window, to lock the last sash against being lowered, and to also lock the lower storm window sash against being raised, said screen also adapted to be positioned upon said support, with the upper edge of the screen contacting said lower sash, to permit the lower storm sash to be raised, and said support also serving as a hand grip whereby to raise the lower storm sash.
